MOVING STAIRWAY HANDRAIL
PROTECTIVE DEVICE

Leon Wieder, Bronx, N. Y., assignor to Otis Elevator Company, New York, N. Y., a corporation of New Jersey

Application March 25, 1939, Serial No. 264,088

6 Claims. (Cl. 198—16)

The invention relates to protective devices for the handrails of moving stairways.

Moving stairways are provided with moving handrails for the convenience of persons using the stairways. Two handrails are provided, one on each side of the stairway. These handrails slide on guides secured to the stairway balustrading and at the ends pass around newel wheels. Openings are provided in the balustrades at each end for the handrails, the handrails emerging from these openings at the entrance of the stairway and disappearing into these openings at the exit end of the stairway. Due to operating clearances, these openings are somewhat larger than the handrails themselves. Protective devices are provided to prevent the fingers of passengers from being caught between the balustrades and the handrails at the points where the handrails enter the balustrades. These devices are arranged in the handrail openings of the balustrades.

It is the object of the invention to provide for each handrail a device which, if a hand is left in contact with the handrail while passing around the exit newel wheel, will be engaged by the hand as it arrives at a certain distance from the handrail opening to serve as a warning to remove the hand before the handrail opening is reached.

One feature of the invention is the provision of such a protective device which will yield upon being engaged by a hand being held on the handrail, so as to obviate any possibility of injury from the protective device itself.

Another feature of the invention is the provision of such a protective device which, upon being engaged by a hand held on the handrail, will be deflected out of the way but will move into protective position as the hand is disengaged therefrom.

Another feature of the invention is the provision of a protective device for a moving stairway handrail which is of simple construction, reliable in operation and economical to manufacture and install.

Other features and advantages of the invention will become apparent from the specification and appended claims.

In the drawing:

Figure 1 is a view in perspective of the exit end of a moving stairway showing the balustrades equipped with protective devices in accordance with the invention;

Figure 2 is a plan view in section taken above the protective device of Figure 1; and

Figure 3 is a detail of the protective device of Figure 1 as viewed from the front of the balustrade.

Referring to Figure 1, the balustrades of the moving stairway 10 are designated 11 and 12. The handrails 13 and 14 are carried by the newel wheels around the exit end of the stairway through openings 15 in the ends of the balustrades. These openings are considerably larger than the handrails and the space is taken up by brushes 16 arranged in the openings and shaped to conform to the handrails. Protective devices 17 are provided over the handrails a certain distance above the openings. As the construction of the protective device for each handrail is identical, only one of them, say for handrail 14, will be described.

In accordance with the construction illustrated, the protective device comprises a coil spring 20 provided with a cover in the form of a flexible sleeve 21. The spring and cover extend horizontally across the face of the handrail from a point between the handrail and the outer side of the balustrade to form a guard. The strength of this spring is such that it normally remains in position across the face of the handrail but readily yields when engaged by a hand in contact with the moving handrail. One end of the spring is secured to an end piece 23 in a depression 24 formed in the end piece. The other end of the spring is secured to a bracket 22 in a similar depression formed on the bracket. The flexible cover 21 for the spring is in the form of a rubber hose of an internal diameter to fit the spring. The end piece 23 is tapped longitudinally to receive a screw 28 for securing a tip 30 to the end of the spring. This tip, which is preferably of fiber, is the same diameter as the outside of cover 21 and is rounded off.

The guard is mounted parallel to the outer surface of the handrail and in close proximity thereto. It is secured to the balustrade by bolt 31 extending through bracket 22 and spacing block 32. This spacing block may be of a finish and design to correspond or blend with the balustrade. Lugs 33 formed on bracket 22 extend into depressions in spacing block 32. This, together with the fact that the inner surface of the spacing block 32 is curved to correspond with the curvature of the balustrading, maintains the guard normally in a horizontal position. The guard is secured to the balustrade at such point laterally that the guard does not extend all the way across the face of the handrail, the tip end 35

of the guard being back from the side of the handrail as illustrated.

In operation, so long as nothing comes in contact with the guard, it remains in position extending horizontally over the face of the handrail. However, should the hand of a person using the stairway remain in contact with the handrail until the guard is reached, it strikes the guard, which immediately deflects to obviate any injury to the hand. However, upon his hand being struck, the person instinctively releases the handrail and thus his hand is not carried to the handrail opening. As the guard is disengaged by the hand, it returns to its horizontal position across the face of the handrail.

It has been found by observation that about the only persons leaving their hands in contact with the handrail as the handrail passes around the newel wheel are small children around four years of age. It is preferred, therefore, to position the guards at an optimum position for serving as a warning for children of this age. Positioning of the guard about eight inches above the handrail opening has been found satisfactory for this purpose, this distance allowing ample opportunity for the child to remove his hand from the handrail after engaging the guard before the handrail opening is reached. The end of the guard being back from the side of the handrail minimizes the possibility of any clothing being caught by the guard and, as the tip of the guard is rounded and of fibrous material, it permits any clothing which does accidentally contact the tip of the guard to slide off readily without being caught.

The above described construction is one which has been found satisfactory in actual installation. It is to be understood, however, that the construction of the guard may be varied considerably and that the positioning of the guard with respect to the handrail and its distance from the handrail opening may be altered to suit any particular installation. It is intended that many variations in construction and arrangement of the protective device may be made within the spirit and scope of the invention so long as the device is mounted so as to engage any hand held on the handrail in ample time for the hand to be removed before reaching the handrail opening and will yield upon being so engaged so as to obviate being a hazard in itself.

What is claimed is:

1. A protective device for a handrail opening in the balustrade at the exit of a moving stairway comprising, an elongated guard, and means mounting said guard at one end on the balustrade in position extending crosswise over the face of the handrail at a point in sufficient advance of said opening to permit the hand, upon striking said guard, to be removed before the opening is reached, said guard being deflectible so

as to move out of the way upon being struck by a hand and being biased to protective position so as to return thereto as the hand is disengaged from the guard.

2. A protective device for a handrail opening 5 in the balustrade at the exit of a moving stairway comprising, an elongated resilient guard, and means mounting said guard at one end on the balustrade with the other end free and extending crosswise over the face of the handrail and 10 in close proximity thereto at a point above said opening.

3. A protective device for a handrail opening 15 in the balustrade at the exit end of a moving stairway comprising, an elongated coil spring, a 15 cover for said spring, and means securing said spring to the balustrade above said opening and in position extending substantially horizontally over the face of the handrail.

4. A protective device for a handrail opening 20 in the balustrade at the exit end of a moving stairway comprising, an elongated coil spring, a flexible cover for said spring, a rounded tip for one end of said spring, and means securing said spring at its other end to the balustrade above 25 said opening and in position extending horizontally over the face of the handrail and parallel therewith in close proximity thereto.

5. A protective device for a handrail opening 30 in the balustrade at the exit end of a moving 30 stairway comprising, an elongated coil spring, a flexible rubber hose forming a cover for said spring, a rounded fiber tip covering one end of said spring, and means securing said spring at its other end to the balustrade a certain distance 35 above said opening and in position extending horizontally across the face of the handrail to within a certain distance of the inner side of the handrail and with its cover in close proximity thereto.

6. A protective device for a handrail opening 40 in the balustrade at the exit end of a moving stairway comprising, an elongated coil spring, a flexible rubber hose forming a cover for said spring, a rounded fiber tip for one end of said spring of 45 the same diameter as the external diameter of said hose and secured to said one end of the spring in abutting relation with said hose, a bracket secured to the other end of said spring, a spacing block, and a bolt extending through 50 said bracket and block securing said spring to the balustrade in position extending horizontally from said bracket over the face of the handrail to a point with the tip end short of the inner side of the handrail and with said spring approximately eight inches above the handrail opening, said spacing block positioning said spring substantially parallel with the face of the handrail and with its cover in close proximity thereto.
